JEAN SCHÄFER, OF PARIS, FRANCE.

SEPARATING AND PURIFYING APPARATUS FOR LIQUIDS.

Application filed May 31, 1927, Serial No. 195,539, and in France June 15, 1926.

This invention has for object an apparatus adapted to separate liquids of different densities. It is particularly applicable to the purification of gasoline and then serves to 5 separate the drops of water or other liquids heavier than gasoline and, moreover, to free it from other foreign bodies or impurities it may contain.

This apparatus is essentially characterized 10 by a closed chamber wherein passes the liquid to be purified, this chamber permanently containing a liquid heavier than the preceding one and nonmiscible with it, for instance water, on which the first, for instance, gasoline, line, passes, the level of the heavy liquid being 15 constantly maintained between two well determined limits.

The invention is characterized, moreover, 20 by a float arranged in the above-mentioned chamber, carrying two closing members, one capable of acting on the flow of the gasoline, or other liquid to be purified, the other on that of the water, and so arranged that, in case of excess of heavy liquid suddenly occurring, the passage of the light liquid will 25 then be closed.

Another feature of the invention is that the gasoline, when entering the apparatus, 30 encounters a partition or surface, which determines the separation of the elements of different density and that, also at the inlet of the apparatus, is arranged a filtering surface stopping the solid materials.

The invention is further characterized by 35 the application in the apparatus—and consequently before the carburetor—of means adapted to simultaneously render regular the flow of the fluid fuel at the same time as to purify it.

40 In a method of carrying out the invention, the wall upon which strikes the jet of gasoline is perforated with one or more orifices through which the said combustible fluid passes from the exterior to the interior of the 45 chamber, this regularizing the movement of this fluid.

Preferably, this orifice is provided in a groove formed exteriorly to the member, specifically the body of the plug of the apparatus.

The accompanying drawing, given by way of example only, illustrates in Figures 1 and 2 a method of carrying out the invention and in Figure 3, a modification.

55 Fig. 1 is a vertical section.

Fig. 2 is a corresponding plan view.

Fig. 3 is a section of a modification.

Fig. 4 is a horizontal section made according to A—A of Fig. 3.

As illustrated in the drawing, the apparatus comprises a vat *a* on which is screwed a part *b* constituting a lid; the joint between these two parts is ensured by engagement of a rib *a*¹ of triangular cross section into a groove *b*¹ of rectangular cross section. This 60 method of junction avoids the use of any auxiliary means, such as leather, packing, etc.

In the part *b* is formed a chamber *c* closed by a screw-threaded plug *d*, and into which 70 the admission of the liquid to be purified takes place. This liquid is admitted through a pipe *e* connected to the part *b* and opening in the chamber *c*.

The plug *d* is provided with a part *f* projecting inside the chamber and opposite the pipe *e*; so that the liquid entering the apparatus strikes against this part *f*. Underneath is arranged a movable perforated member *g*¹, supporting a wire gauze *g*; a spring *g*² holds this wire gauze in fixed position.

The lower part of the chamber *c* communicates with the vat *a*. In the latter is a float *h*, made of cork for instance, carrying a rod *h*¹, on which is formed, on the one hand, a 85 conical ring *i* and, on the other hand, a needle valve *j*. The ring *i* can strike against a channel *k* through which issues the purified liquid; a pipe *k*¹ connects the apparatus to the carburetor. The needle valve *j* can fit upon 90 the inlet of a pipe *l*, connecting the vat to another tank *m*, which is closed and is provided with a U-shaped pipe *n*.

The operation is as follows:

The apparatus is first filled with a liquid 95 heavier than the liquid to be purified and of suitable nature and in general, the heavier of the liquids to be separated. For instance, in the case of gasoline, the apparatus is filled with water. For that purpose, the plug 100 *d* is removed and water is poured and fills the vat *a* and tank *m* up to the level *Z*—*Z'*.

At this moment the U-shaped tube *n* fills up and the water flows away until the level has reached the line *Y*—*Y'*; at this moment, 105 the U-shaped tubes empties. The plug *d* is put back into place. If the liquid to be purified is then admitted through the pipe *e* into the apparatus and this liquid fills up the space which has remained empty in the apparatus, passes over the water filling the vat *a*, and issues through the channel *k* and the 110

tube k^1 . But, by passing through the apparatus it has been purified; in fact, in the first place, by encountering the boss f of the plug d , owing to the change of direction and even of the shock of the liquid against this boss, a separation of the liquids of different densities takes place. For instance, the small drops of water are collected to form larger drops of water and these fall more quickly than gasoline. The wire gauze does not stop them and they collect within the mass of water contained in a and m . The solid impurities are stopped by the wire gauze g . The liquid which arrives at k has therefore been purified.

The water collecting in the vat a , its level rises; at a certain time the float h is lifted this allowing a certain quantity of this water to pass into the tank m . When the water level in this tank m reaches the line $Z Z'$, the U-shaped tube fills up and an automatic blow through action takes place.

The new device can be placed at any point relatively to the apparatus it must feed. In the case of a carburettor, it is placed before the latter on the gasoline pipe line. It can also be integral with the carburettor and the vat a can be the lower extension of the chamber of the carburettor.

In the form of construction of Figs. 3 and 4, the apparatus comprises again, a vat a , on which is screwed a lid b in which is formed a chamber c in which arrives the liquid admitted through e ; this chamber has a wall f upon which takes place the shock determining the separation of the liquids of different densities. The vat a always contains a certain quantity of water the level of which can vary from a lower level N^1 to an upper level N^s .

The float h is rigid with the rod h^1 carrying at each of its ends a needle valve. The upper needle valve i is adapted to close the passage of the lightest liquid, gasoline for instance when the float reaches the upper portion of its stroke. The lower needle valve j is adapted to close a conduit l which is a blow through conduit. The latter is normally closed by another needle valve q carried by a screw plug p .

The plug d is provided with an orifice d^1 which, preferably, is formed approximately in the plane of the axis of the gasoline feeding conduit e .

This orifice is provided in a groove u formed externally to the wall of the plug.

Instead of a single orifice, several orifices might be distributed on the periphery of the groove u .

The operation is as follows:

Let us suppose the apparatus is placed for instance between the gasoline tank and a carburettor.

It must be filled with a certain quantity of water. For filling it, the plug d is removed,

the plug p is unscrewed and water is poured. This water is first retained in the vat, since the needle valve j rests upon, its seat. As soon as the water reaches the level N^s , the float rises and the needle valve j opens. The excess of water flows away through the hole r and the level comes to N^1 . The apparatus is then ready to operate; the plug d is screwed on again. The plug p is also screwed on again, although this is not indispensable. 75

When gasoline is caused to enter through e , it encounters the wall f . Under the action of the shock, the drops of water separate and collect into larger drops. These pass with the gasoline through the filter g and fall more quickly than gasoline in the vat. The solid particles are retained by the filter g .

The water, or other liquid heavier than gasoline, accumulates in the vat a , and causes the level of the separation plane of the two liquids to rise. The gasoline which passes over the water abandons its last impurities, fatty matters, etc. and after being thus purified proceeds through the passage s and the conduit k , k^1 to the carburettor. 90

When by accumulation of the impurities the plane of separation reaches the level N^s , the float sufficiently rises for causing the needle valve i to close the passage for the gasoline. The admission of gasoline being then stopped, one is thus warned that it is necessary to empty the apparatus. In order to do this; it suffices to unscrew the plug p and the heavy liquid can flow to the exterior; when the flowing away ceases. The plug p is 100 screwed on again. The level has automatically been re-established at N^1 .

It will be noted that not a single drop of water can pass to the carburettor, since as soon as the water level reaches N^s the operation is stopped. On the other hand, there is no loss of gasoline, the latter always flows above the water, even during the blow through operation.

The apparatus allows the use of very heavy 110 fuels with all engines, even with engines of high speed and having a small volume of charge, and even with super-compressed engines, this allowing to obtain a very substantial economy for an equal power.

The cleaning of the gasoline by water produces a remarkable purification.

The gasoline by contact with water is freed of all its impurities which pass into this water, so that when the blow through operation is effected they are eliminated at the same time.

The apparatus can be cleaned when desired, either with gasoline or with water.

The products of this cleaning operation 125 can be poured again in the tank, these products being subsequent by and automatically sorted out by the apparatus.

The orifice or orifices d^1 have for effect to regularize the flowing away of the fluid ar- 130

riving through the conduit *e*. This fluid strikes against the wall *f* of the plug body as explained above. The liquid then passes, through the hole *d*¹ within the plug, and from there comes to the filter *g*. Experience shows that the results obtained in these conditions are better.

The device forming the subject-matter of this invention and interposed between the 10 fuel tank and the carburettor, effects retarding the flow of the gasoline. It is known that, upon restarting of the engine, a sudden suction of gasoline takes place. In carburettors directly connected to the engine, nothing prevents the afflux of gasoline in the vessel. A 15 serious inconvenience results therefrom: a real wasting of fuel not only occurs, but, moreover, the carburetted mixture contains such an excess of gasoline that it burns badly 20 and that the restarting is often choked.

With the new apparatus, the admission of gasoline in the carburettor is slowed down, owing to the changes of direction and to the interposition of the orifice *d*¹ and of the filter 25 and the inconvenience which has just been indicated is avoided. The presence of the passage *d*¹ diminishes the pressure of the gasoline and prevents it from entering in too 30 large quantity into the carburettor upon restarting.

It is to be understood that the various passages and cross sections are given the required values for obtaining a suitable slowing down 35 of the gasoline without preventing the engine from reaching its maximum power.

Claims:—

1. In a separating and purifying device for mixed liquids of different specific gravity, a vat having an inlet and two outlets, one of 40 the latter for each of the separated liquids, means for automatically maintaining a constant level of the heavier liquid in said vat, a surface in the liquid inlet chamber against which the liquid to be purified strikes, said 45 surface having a groove and orifices for the passage of the separated liquids formed in said groove.

2. In a separating and purifying device for mixed liquids of different specific gravity, 50 a vat having an inlet and two outlets, one of the latter for each of the separated liquids, a fixed quantity of the heavier liquid contained in the vat, a float in said vat, a rod rigid in said float terminated by two needle 55 valves, one closing in one position of the float, the heavier liquid outlet and the other closing in another position of the float the

lighter liquid outlet, a member fitting on the vat carrying the inlet and one of the outlets having a screw-threaded opening therein, a 60 plug screwed in said opening, and a filter placed in the bottom of the plug housing.

3. In a separating and purifying device for mixed liquids of different specific gravity, a vat having an inlet and two outlets, one of the 65 latter for each of the liquids, a fixed quantity of the heavier liquid contained in said vat, a float in said vat, a rod rigid with said float terminating in two needle valves, one closing in one position of the float the heavier liquid 70 outlet, a member fitting on the vat carrying the inlet and one of said outlets having a screw-threaded opening therein, a plug screwed in said opening, said plug carrying a wall forming an extension and upon which 75 the mixed liquid strikes and a filter placed in the bottom of the plug housing.

4. In a separating and purifying device for mixed liquids of a different specific gravity, a vat having an inlet and two outlets, one of the latter for each of said separated liquids, a fixed quantity of the heavier liquid contained in said vat, a float in said vat, a rod rigid with said float terminating in two needle valves, one closing the heavier liquid 80 outlet, a member fitting on the vat and carrying the inlet and one of the outlets having an opening therein, a plug screwed in said opening, said plug carrying a wall forming an extension and upon which the mixed 85 liquid strikes, and a filter placed at the bottom of said plug housing, said walls having orifices formed therein.

5. In a separating and purifying device for mixed liquids of different specific gravities 95 a vat having an inlet and two outlets, one of the latter for each of said separated liquids, a fixed quantity of the heavier liquid filling said vat, a float in said vat, a rod rigid with said float terminated by two needle valves, one closing in one position of the float the heavier liquid 100 outlet, a member fitted on the vat carrying said inlet and one of said outlets and having a screw-threaded opening therein, a plug screwed in said opening, said plug carrying a wall forming an extension and upon which 105 the mixed liquid strikes, and a filter placed in the bottom of the plug housing, said plug being provided with a groove in said wall and having orifices provided in said groove. 110

The foregoing specification of my "Separating and purifying apparatus for liquids" signed by me this 20th day of May, 1927.

JEAN SCHÄFER.
